UNITED STATES PATENT OFFICE.

CHARLES H. KELLOGG, OF BUFFALO, NEW YORK.

SEPARATOR FOR GIRDERS.

No. 852,685.

Specification of Letters Patent.

Patented May 7, 1907.

Application filed November 12, 1906. Serial No. 342,949.

To all whom it may concern:

Be it known that I, CHARLES H. KELLOGG, a citizen of the United States, residing at Buffalo, in the county of Erie and State of New York, have invented a new and useful Improvement in Separators for Girders, of which the following is a specification.

This invention relates to the separators employed for properly spacing the beams of iron girders.

The separators in common use consist of cast-iron plates having integral lugs for the passage of the bolts which tie the beams together. Such separators have the objection that their lugs are liable to be broken off in shipment. They are also subject to variations due to shrinkage of the metal, and when this is the case they fit loosely between the beams and do not properly transmit the superposed load from one beam to the other.

The object of my invention is the provision of a light and inexpensive separator which will accurately fit the beams so as to evenly distribute the load and which possesses the necessary strength to resist breakage of its bolt-receiving member or attachment under the rough usage to which such articles are subjected.

In the accompanying drawings: Figure 1 is a cross section of an I-beam girder provided with the improved separator. Fig. 2 is a horizontal section in line 2—2, Fig. 1. Fig. 3 is a perspective view of the separator. Figs. 4 and 5 are similar views of modified constructions of the same.

Similar letters of reference indicate corresponding parts throughout the several views.

The girder illustrated in the drawings is composed of a pair of parallel I-beams A tied together at suitable intervals by the usual bolts, one of which is shown at B, but the invention is equally useful in connection with girders consisting partly or wholly of channel or other beams.

Referring to Figs. 1, 2 and 3, C indicates the separator which consists of a pressed steel plate of suitable thickness and of the proper outline to closely fit the webs and flanges of the opposing beams, as shown in Fig. 1. This plate is provided with seats or bolt-engaging portions formed integral therewith and bent or pressed out of the general plane thereof in opposite directions, so that the seats receive and embrace opposite sides of the tie bolt for retaining the separator in

place. In the construction shown in Figs. 1, 2 and 3, the plate is provided centrally with a semi-circular horizontal loop d which embraces one side of the tie bolt and is pressed up from one side of the plate, and on opposite sides of said loop with semi-circular horizontal seats or grooves e which embrace the other side of the bolt and are formed by pressing up the opposite side of the plate, forming three bearing points or surfaces for the bolt. As is evident from an inspection of the drawings, two parallel upright slits are formed in the separator before pressing up said loop and seats. The metal forming these parts is not stretched, but is simply bent or pressed in opposite directions without drawing it or reducing its thickness, the pressing operation shortening the separator blank to the extent that its middle portion is bent or deflected to form the loop d and the seats e. The metal therefore retains its original strength and toughness and the loop is not liable to be fractured in pressing the blank or to be broken by rough handling or in shipment. In addition to this important advantage, the separator is comparatively light, it can be cheaply produced, and being formed of sheet steel, it can be accurately cut to snugly fit the beams of the girders, thus reliably transmitting the load from one beam to the other and evenly distributing it.

The arrangement of the bolt-seats of the separator may be modified without departing from the essence of the invention. Fig. 4, for example, shows a modification in which the central loop d of the first-described construction is omitted and the separator plate C¹ is provided on opposite sides of a central slit with bolt-seats e¹ extending from the slit to the lateral edges of the plate and pressed outwardly in opposite directions, forming two bearings for the bolt.

Fig. 5 shows another modification similar to that illustrated in Fig. 4 but differing therefrom in that the plate C² has a comparatively large central opening f which separates the oppositely-pressed bolt-seats e².

The separator shown in the drawings has a single set of bolt-seats, but it may obviously have two or more sets for receiving a corresponding number of tie-bolts according to the height of the girder.

I claim as my invention:

1. A pressed-metal separator for girder-beams, consisting of a plate having an inte-

gral attaching member bent up from the side thereof and constructed to embrace a tie-bolt of the beams, substantially as set forth.

2. A pressed-metal separator for girder-beams, consisting of a plate having integral bolt-embracing seats pressed outward from the side thereof in opposite directions, substantially as set forth.

3. A pressed-metal separator for girder-beams, consisting of a plate provided with integral bolt-embracing seats pressed outward beyond the sides thereof in opposite directions and having the same thickness as the plate, substantially as set forth.

4. A pressed-metal separator for girder-beams, consisting of a plate provided on one side with a bolt-embracing loop and on its other side with bolt-embracing seats arranged on opposite sides of the loop, said loop and seats being integral with the plate and pressed outward therefrom in opposite directions, substantially as set forth. 15
